(21) Appl. No.: **29/175,002**

CLAIM

(22) Filed: **Jan. 29, 2003**

The ornamental design for a surface configuration of an instrument display for a vehicle, as shown and described.

(30) **Foreign Application Priority Data**

DESCRIPTION

Aug. 30, 2002 (DE) 402 07 222

FIG. 1 is a right perspective view of a surface configuration of an instrument display for a vehicle according to my novel design;

(51) LOC (7) Cl. **12-16**

FIG. 2 is a left perspective view of the surface configuration of an instrument display for a vehicle according to my novel design;

(52) U.S. Cl. **D12/192**

FIG. 3 is a front view of the surface configuration of an instrument display for a vehicle according to my novel design;

(58) Field of Search D12/192, 114;

FIG. 4 is a right side view of the surface configuration of an instrument display for a vehicle according to my novel design; and,

D10/98, 123-126; 180/90; 296/70, 190-191;
280/752, DIG. 5

FIG. 5 is a left side view of the surface configuration of an instrument display for a vehicle according to my novel design.
